UNITED STATES PATENT OFFICE.

ADELBERT AMES, JR., OF TEWKSBURY, MASSACHUSETTS.

LIGHT-SIGNALING.

1,339,085.

Specification of Letters Patent.

Patented May 4, 1920.

Application filed June 21, 1917. Serial No. 176,081.

To all whom it may concern:

Be it known that I, ADELBERT AMES, Jr., a citizen of the United States, and resident of Tewksbury, in the county of Middlesex and State of Massachusetts, have invented new and useful Improvements in Light-Signaling, of which the following is a specification.

This invention relates to a method and apparatus for signaling with light by intermittently projecting flashes of light, the flashes preferably being projected according to a predetermined code.

The principal object of the invention is to provide a method and means for signaling with light in a more convenient and effective manner than has heretofore been possible. Another object of the invention is to provide means for intermittently flashing beams of light without either extinguishing the light or shading the projector. Another object is to project intermittent flashes of light which are sharply defined, that is, flashes which begin abruptly and terminate abruptly, so that signals may be transmitted at a rapid rate and so that they may be readily distinguished.

Other objects of the invention will be apparent from the following description and the accompanying drawings, in which,—

Figure 1 is a vertical central longitudinal section of the preferred embodiment of my invention; and

Fig. 2 is a plan view of the apparatus, a part being broken away.

The particular embodiment of my invention chosen for the purpose of illustration comprises in general a reflector 1 adapted to project light emanating from its focus in the form of a concentrated beam, this reflector preferably being parabolic in contour, a light source 2 which preferably comprises an incandescent bulb containing a filament of suitable shape, a casing 3 for closing the reflector, light source and other parts, and a transparent front cover 4. The transparent front cover may be mounted on the apparatus in any suitable manner but it is preferably mounted somewhat in advance of the forward periphery of the reflector 1. In the illustrated embodiment this is effected by providing a cylindrical extension 6 on the forward edge of the casing 3, the transparent front cover being mounted on the extension 6 by means of an annular member 7 secured to the extension 6 by

means of screws 8. The extension 6 serves to prevent light radiating laterally from the light source, and it also affords more space within the housing so that the light source 60 may be moved axially within the apparatus, as hereinafter described.

In accordance with the objects of the invention, the light source is so mounted in the apparatus that it may be moved into and out of the focus of the reflector 1. When the light source is in the focus a concentrated beam is projected by the apparatus, and by employing a concentrated light source and a parabolic reflector the beam of light produced by the apparatus can be made substantially cylindrical so that it will carry a great distance. When the light source is moved out of the focus, even a distance as small as an inch or two, the light is so dispersed that the concentrated beam is entirely broken up and consequently the light will not carry any appreciable distance. While the flashes of light may be produced by moving the light in and out of focus in either a curved or a straight line, I preferably arrange the apparatus so that the light source may be reciprocated into and out of focus along the axis of the reflector, the mounting means preferably being disposed 70 in the rear of the reflector.

The particular means for movably mounting the light source which I have chosen to illustrate my invention comprises a tubular member extending axially from the rear of the casing 3, the tubular member preferably comprising a portion 11 of relatively large diameter and a portion 12 of smaller diameter. The tubular member 11—12 is preferably formed integrally with the casing 3 90 and is closed at its rear end by means of a cap 13 threaded into the smaller portion 12 of the member. The light source 2 is mounted through the medium of its socket 14 upon a tubular member 16 telescoping with the 100 smaller portion 12 of the outer tubular member. The preferred means for reciprocably mounting the member 16 in the member 12 comprises two sleeves 17 and 18 which fit into the member 12 and which fit 105 around the member 16. The members 17 and 18 may be secured to the member 12 by any suitable means, as for example, by means of a driving fit, and are adapted to permit the member 16 to slide freely therethrough. In order to reciprocate the member 16 a sleeve 19 is secured to the member 110

16 between the sleeves 17 and 18, the sleeve 19 having laterally extending arms 21 projecting outwardly through slots. On the projections 21 are mounted arms 24 which 5 preferably extend outwardly and forwardly into proximity to the periphery of the projector casing, the arms 24 being secured to the projections 21 in any suitable manner, as for example, by brazing. The sleeve 19 10 is secured on the tubular member 16 at such position longitudinally of the tube 16 that when the sleeve 19 abuts against sleeve 17 the light source is disposed in the focus of the reflector, and that when the reciprocating 15 parts are moved rearwardly into the position shown in Figs. 1 and 2, that is, with the sleeve 19 abutting against sleeve 18, the light source will be sufficiently displaced from the focus of the reflector as to prevent 20 the formation of a concentrated beam of light; although it is to be understood that the stops 17, 18 and 19 may be relatively so disposed that the light source is in the focus when the stop 19 abuts against stop 18. 25 In order normally to hold the light source in one of its two extreme positions, I provide yielding means in the form of a coiled spring 24. The yielding means may be so arranged as to hold the light source in either 30 of its extreme positions, but I prefer to so arrange the means as normally to hold the light source out of focus. I have therefore illustrated the spring as being a compression spring, acting at one end against the 35 casing 3, and at the other end against the reciprocating parts. The spring acts against the casing 3 through the medium of a flanged ring 26 secured to the casing by means of screws 27 and the spring acts on 40 the reciprocating parts through the medium of a flanged disk 28 threaded upon the tubular member 16. The conductors 31 for supplying current to the light source may be led into the apparatus in any suitable manner, but I prefer to lead them through a 45 slot 32 in the member 12 and thence into the rear end of the tubular member 16.

In operating the apparatus the light source is reciprocated into and out of focus 50 intermittently in such manner as to project flashes of light according to a predetermined code. The arms 24 are arranged to extend into proximity to the periphery of the casing 3 so that when the apparatus is 55 gripped on opposite sides in the two hands of the operator he may reciprocate the light source forwardly into focus by pressing forwardly on the hooked ends of the arms 24 with his thumbs. In this way the beam of 60 light may be accurately aimed at the signaling receiving station and at the same time be readily operated by the transmitting operator. The preferred method of employing 65 the apparatus is to mount the casing 3 on a tripod so that it may be rotated both

vertically and horizontally, but inasmuch as the mounting means comprises no part of the present invention it has not been illustrated.

If the light source be axially moved out 70 of the focus only a small fraction of an inch in either direction the beam spreads out into the form of a cone having a hollow center and the farther the source is removed from the focus the greater the spread of the cone 75 and the greater the size of the hollow or dark center. Consequently, by aiming the apparatus directly at the receiving station signals may be transmitted by moving the light source only the small amount necessary to produce a dark center in the beam and without totally destroying the beam. 80

The difficulty experienced with light signaling apparatus in which the circuit of the lamp is opened and closed to flash the signals, namely, the difficulty of the signals merging into each other due to the slow rate at which the filament heats and cools, is overcome by my apparatus and the signals may be transmitted at a very rapid rate owing 85 to the fact that they begin and end abruptly. 90

I claim:

1. Signaling apparatus comprising a reflector adapted to reflect light emanating 95 from its focus in the form of a concentrated beam, a light source, means for movably mounting the light source relatively to the reflector so that it can be moved into and out of focus, and yielding means for normally holding the light source out of focus, the yielding means being adapted to yield sufficiently to permit the light source to be moved into focus against the action thereof, whereby light signals may be transmitted 100 by intermittently moving the light source into focus against the action of said yielding means. 105

2. Signaling apparatus comprising a reflector adapted to reflect light emanating 110 from its focus in the form of a concentrated beam, a light source, means for movably mounting the light source so that it may be moved into and out of focus, the apparatus being adapted to be held in the hand and having means for moving the light source extending into juxtaposition to the hand holding position, whereby the light source may be moved relatively to the reflector by 115 the hand holding the apparatus. 120

3. Signaling apparatus comprising a reflector adapted to reflect light emanating from its focus in the form of a concentrated beam, a light source, means for movably mounting the light source so that it may be 125 moved into and out of focus, the apparatus having two lateral hand holding positions and having means extending into juxtaposition to said positions for moving the light source, whereby the apparatus may be sup- 130

ported and directed by both hands and at the same time be actuated by one or both hands.

4. Signaling apparatus comprising a reflector adapted to reflect light emanating from its focus in the form of a concentrated beam, a light source, means for movably mounting the light source along the axis of the reflector so that it may be moved into and out of focus, and an arm extending laterally from the mounting means into proximity to the periphery of the reflector for controlling the movement of the light source.
5. Signaling apparatus comprising a reflector adapted to reflect light emanating from its focus in the form of a concentrated beam, a light source, a socket member fixedly mounted along the axis of the reflector, a plunger member arranged to reciprocate in the tubular member, the plunger member supporting the light source in the region of the focus of the reflector and being arranged to move the light source into and out of focus

as it is reciprocated in the tubular member, and a pair of arms extending outwardly 25 from the plunger member through slots in the tubular member for controlling the movement of the light source.

6. Signaling apparatus comprising a reflector adapted to reflect light emanating 30 from its focus in the form of a concentrated beam, a tubular casing extending axially from the rear of said reflector, an electric lamp normally having its socket disposed in the forward end of said casing and its light 35 source in the rear of the focus of said reflector, a member extending rearwardly from said socket in said casing and having a sliding fit with the casing, a spring surrounding said socket to urge said lamp rearwardly, 40 and means for advancing said lamp into focus extending laterally from said member through a slot in said casing.

Signed by me at Boston, Massachusetts,
this 7th day of June, 1917.

ADELBERT AMES, JR.
